[57] CLAIM

The ornamental design for a beverage can holder, as shown and described.

DESCRIPTION

FIG. 1 is a top, front, right side perspective view of a beverage can holder showing my new design;

FIG. 2 is a top plan view thereof;

FIG. 3 is a front elevation view thereof, the can shown in broken lines for illustrative purposes only; and

FIG. 4 is a side elevation view thereof, the undisclosed rear and bottom views thereof being mirror images of FIGS. 3 and 2 respectively.

FIG. 2

FIG. 4
